UNITED STATES PATENT OFFICE.

LOUIS J. VAN GUELLEN, OF CINCINNATI, OHIO.

SHOE-BUTTONING MACHINE.

1,415,737.

Specification of Letters Patent.

Patented May 9, 1922.

Application filed April 3, 1918. Serial No. 226,544.

To all whom it may concern:

Be it known that I, LOUIS J. VAN GUELLEN, a citizen of the United States, residing at Cincinnati, in the county of Hamilton and State of Ohio, have invented certain new and useful Improvements in Shoe-Buttoning Machines, of which the following is a specification.

The object of my invention is to produce a machine for buttoning shoes in the shoe factory before said shoes are sent to the lasting room, in order to maintain a uniform and proper shape and contour to the shoe, during the progress of manufacture.

By the process now in vogue, five buttons are usually buttoned by hand. If the shoe has a smaller number of buttons, then less than five buttons are buttoned. I do this buttoning by machinery.

In carrying out my invention, I provide means or finger mechanism for grasping and holding the buttons on a button fly; and provide mechanism for opening and closing said mechanism around the buttons, and in

connection with this mechanism I provide means for pushing the button fly over the buttons on the button fly, after this is done I provide means for opening the finger mechanism for grasping the buttons, after

the flies have been buttoned and then provide means for pushing the button fly and the button hole fly, after they have been buttoned together, out of the machine, and after this is done I provide means for re-closing the means for grasping the buttons and operate the means which push the button hole fly over the buttons on the button fly back to normal position, for the next operation.

Inasmuch as the space between the buttons, from center to center often varies, on account of different makes of shoes, I provide means for adjusting the mechanism that it will operate in connection with shoes having their buttons and button holes spaced to a greater or lesser extent. The means employed for grasping and holding the button is stationary and the means for pushing the button hole fly over the buttons

moves upward and downward; upward to push the button hole fly over the buttons and finally to expel the buttoned flies out of the machine, and downwardly to normal positions.

The various features of my invention and their advantages will be readily apparent and understood from the following specification and claims.

In the accompanying drawings, forming part of this specification:

Fig. 1, is a side view of the machine, taken on the line 1—1 of Fig. 2,

Fig. 2, is a plan view of the machine,

Fig. 3, is a side view of the machine, being the opposite side to that shown in Fig. 1, and partly broken away,

Fig. 4, is a plan view of Fig. 3, taken when looking in direction of arrow,

Fig. 5, is a section taken on line 5—5 of Fig. 4,

Fig. 6, is a section taken on line 6—6 of Fig. 5,

Fig. 7, is a plan view taken on line 7—7 of Fig. 5,

Fig. 8, is a section on line 8—8 of Fig. 2,

Fig. 9, is a front view of one of the button fingers used by me, shown closed, in connection with a pushing finger which operates therewith,

Fig. 10, is a plan view of the head of the machine, showing preferable form of push finger mechanism,

Fig. 11, shows the same parts as Fig. 10, except the view is taken from the front looking up at the mechanism shown in said figure,

Fig. 12, is a section on line 12—12 of Fig. 11; parts broken away to show construction and some parts unsectioned,

Fig. 13, is a view in elevation and a view in section of one of the finger supports,

Fig. 14, is a front elevation of the machine,

Fig. 15, is a view in elevation of a button finger and connections, with the button clasping jaws closed and the pusher fingers in their normal position, with a part of the button hole fly of the shoe pushed over the closed fingers, thus illustrating the first step of the operation.

Fig. 16, is a similar view of the parts shown in Fig. 15 and illustrates the next step in the operation, the button clasping jaws being open to receive the button,

Fig. 17, is a similar view of parts as 105 shown in Fig. 16, however showing the other part of the shoe upper, (being the button fly), having the buttons thereon, and

showing one button clasped by the button fingers and illustrating the next step in the operation.

Fig. 18, illustrates, through the medium 5 of the same parts, the next step in the operation, showing the pusher fingers pushing the button hole fly over the button, which is in the button clasping jaws of the fingers,

Fig. 19, is a view of the same mechanism, 10 showing the buttoned shoe and the pusher fingers at their highest point, the button fingers being shown closed, as they appear after expelling the button,

Fig. 20, is a view of the button fingers 15 holding a button between them, in closed position,

Fig. 21, is a view of one side of a button finger, to show the top part, by which the button is clasped or grasped, and

20 Fig. 22, is a front view of one of the button fingers used by me, shown open, one pusher finger also shown and one omitted to to illustrate construction of finger.

I provide a body part in the form of a 25 housing 1, preferably of a U shape, open at the rear, and supported on legs 2.

At the rear of the housing 1, I place a cam shaft 3 journaled in the side walls of said housing. On this shaft 3 I provide, 30 within the housing, two cams 4 and 5, and on one outer end of said shaft I provide a third cam 6; on this shaft at the outer end, where the cam 6 is located, I also provide a large gear wheel 7. On the drive shaft 8, at 35 its inner end, I place a small gear wheel 9, which meshes with the large gear wheel 8. This drive shaft also carries a pulley wheel 10, to which a cylindrical sleeve 12, of a clutch mechanism is attached and which revolves with the pulley wheel. On shaft 8 I also rigidly attach two clutch collars 13 and 14, and collar 13 carries a stop finger 15, (see Fig. 1). This is all that need be stated as to the construction of the clutch 40 mechanism as it is commonly used; its purpose and use herein will, however, be hereinafter referred to.

The cam 4 carries the two noses 16 and 17, (see Fig. 8,) and the cam 5 is of peculiar 50 shape having two noses 18 and 19, (see Fig. 3). Near the front part of the machine, passing through the housing, and extending out at each end, I place a rock shaft 20, and at each end thereof I rigidly connect on 55 said shaft the rock arms 21 and 22, which rock when said shaft is rocked. I also place on this rock shaft 20, a cam lever 23 which extends up over the cam 4, and is provided with a cam roller 24 which rides 60 the face of the cam 4, (see particularly Figs. 2 and 8).

This cam lever 23 is rigidly attached to the shaft 20 by screw 25, (see Fig. 8), and, as the roller 24 passes over the noses 16 65 and 17 of cam 4, the shaft 20 is rocked up

and down or oscillated forward and backward. I also place loosely on said shaft 20, a cam lever 26 which extends over the cam 5, and has a roller 27 which rides the face on said cam 5, (see Figs. 2 and 3).

At the forward part of the machine, on top of the housing 1, I rigidly attach the head 28. This head is provided with gibs or guide ways 29 and 30, in which the finger supports 63 slide, and which will be hereinafter described. At the back end of head 28 I provide two bearings 31, through which I pass the two sliding shafts 32, which at the lower ends are rigidly connected to a cross bar 33, and at the upper parts are 80 rigidly attached to a cross bar 34. From the cross bar 33, depends a stud 35 carrying at its extremity a roller 36, which rides on cam lever 26. On one side of the housing 1, I place a spring bracket 37, a spring 38 extending therefrom up to the lower cross bar 33, (see Fig. 2).

On the cross-bar 34 I attach two forwardly and downwardly extending arms 39, to the forward ends of which I attach two 90 cross bars 40, (see particularly Fig. 5). and on these cross bars 40 I place the pusher finger bar 41, having openings or holes 42. The preferred form of this pusher mechanism or device is shown in Figs. 9, 10, 11 and 95 12, in which I show pusher fingers formed of two pins 42 and 43, one higher than the other, as shown. These push fingers are each mounted on a sliding support 44, which enables them to move laterally as the button 100 fingers pass through them, which operation will be hereinafter set forth.

On the bottom side of head 28, toward the rear thereof, I rigidly attach two shafts 45 on which bearings 46 slide, to which are 105 rigidly attached two cross bars 47, (see Figs. 1 and 3).

On each of the slide bearings 46 I place pins 48, arms 49 extending from these pins to the rock arms 21 and 22, being loosely attached at each end, so that working movement is allowed to said rock arms. On one side a coiled pull spring 50¹ extends from the rock arm 22 to a pin 51² on the housing, (see particularly Fig. 3).

I will now describe one of the button fingers of which there are five, in the present instance. These button fingers are each composed of two jaws 50 and two arms 51 made integral therewith, and extending downward 110 and pivoted by pivot screws 52 to upper and forward end of a housing 53 having a depending hollow stem 54 around which is placed a collar 55, the parts being held together by a nut 56, (see Figs. 5 and 9).

Through the hollow downwardly extending stem 54, I pass the shaft 57 having a cone shaped head 58, (see Fig. 5), threaded at its extremity to receive the nuts 59, having between them a slide block 60. At the 115 120 125

lower end of button finger depending arms 51, I place pins 61 to which is attached a pull spring 62, which pulls the button finger arms together when cone shaped head 58 is released or pulled down, which opens the jaws 50-50, and when the cone shaped head 58 is moved up it opens said arms 51 and closes said fingers 50.

I will now describe the finger supports, 10 which hold the button finger housings 53 in position. These finger supports are numbered 63, and are slotted at 64 and 65; the button finger housing stems 54 passes through slots 65 and through slots 64 pass 15 the adjusting lever pins which will be described later. On the pulley side of the machine, the finger support 63¹ has slot 65 only, this finger support being stationary and the others movable.

20 When the housing stems 54 pass through the slots 65 they are held in position by the collars 55 and nuts 56, the collars impinging against the under side of the finger supports 63. In this manner the housing 53 25 and connections forming the button finger mechanism, and carrying the button fingers 50, can be placed at the desired radius, by unscrewing and retightening the nuts 56. The button finger housing supports 63 support and carry the button finger mechanism, and can be slid to right or left in the ways or gibs 29 and 30 in the housing 28. This must be done in order to operate in connection with shoes in which the button holes 35 are differently spaced, that is, the space between the button holes from center to center varies. It was before stated that one of the button finger supports is stationary and for convenience this one is marked 63¹; the other 40 four move away from and toward said member 63¹. This adjustment of the finger housing supports 63, adjusts the fingers and finger mechanism, that is, when said housing supports are moved to the left or right, the 45 fingers are also moved likewise.

This adjustment operation is as follows: Each of the four finger supports 63 have slots 64, through which lever pins 66 are passed, and are all on a center line of the 50 finger supports 63. On the lower end of each of these pins 66, are rigidly connected one end of crank levers 67, and at the lower end of each crank lever is a fulcrum bearing pin 68, rigidly attached, (see Figs. 5 and 55 12). These crank levers 67 are of different lengths, the shortest one attached to finger support next to the stationary finger support 63¹, and becoming longer as they are spaced therefrom, (see particularly Fig. 6). 60 These levers 67 are made longer as set forth, in order that when the finger supports 63 are spaced they will maintain an equal distance from center to center, no matter to what extent they are moved apart or brought together, and also holding the same distance 65

with the stationary finger support 63¹. At the lower end of fulcrum bearing pins 68, I rigidly attach the crank levers 69, and at their lower ends I place lever pins 70, (see Fig. 12), which pass through hand adjusting slide lever 71 by means of holes 72, which has a bearing 73 at each end of housing 28, (see Figs. 5 and 7).

All these crank levers 69 are of the same length, and hand sliding lever 71 is of peculiar shape, shown in Fig. 7, in order to conform with the irregular centers of fulcrum pins 68, to enable the proper spacing as above set forth.

The large gear 7 drives the cam shaft 3, 80 by reason of small gear 9 meshing therewith, this gear 9 being on the pulley drive shaft 8. The cam 6 has a nose or raised portion 74. In connection with cam 6, I operate a pusher bar 75 passing through bearing 76, having a groove at its forward end and at its rear end is rounded as shown at 78; the bearing 76 is secured to pulley side of housing 1. On the pulley side of the housing 1, at its upper portion, I rigidly 90 connect a bracket arm 79 (see Fig. 2), and from the outer end of this bracket arm, I fulcrum at 80 a depending clutch stop lever 81, which operates in connection with pin 15 on clutch mechanism. From this lever 95 81, near its lower end, I secure a finger 82, which operates in connection with the pusher bar 75 when the machine is operating.

The lever 81 and the finger 82 are also operated by foot power, which mechanism I 100 will now describe.

At front and lower end of housing 1, I place an oscillating treadle shaft 83 which passes through the sides of the housing 1, having at its left side a small lever 84 rigidly connected thereto. To this lever I attach a treadle in any desired manner (not shown), this treadle means being held up by spring 85 connected to a pin 86 at its upper end.

110 At its opposite end the treadle shaft has a lever 87 rigidly connected thereto and extending upward. At its upper end lever 87 has movably attached thereto a hook 88, which hooks over the pin 82. A spring 89 115 extends from the fulcrum point 90, of hook 88 and lever 87, toward the other end of said hook 88, resting on its upper edge and exerting a downward pressure on said hook. On the pulley side of the housing 1, I rigidly attach in front of bracket arm 79, an outwardly and downwardly extending bracket 91, having at its lower extremity a foot 92 carrying an adjusting screw 93, through which the throw out motion of hook 88 is 120 regulated.

The lever 88 has an incline or inclined portion 150 (see Fig. 1), and the screw 93 rides neutral on the straight surface of lever 88 at its fulcrum end and when the foot ex- 130

ertion upon the treadle pulls the lever 87 backward, which in turn pulls the lever 88 in the same direction, the lever 88, which is riding on screw 93, will be pushed upward and be disengaged from pin 82 by the rise of the incline and as the foot pressure is removed, the spring 85, pushes levers 87 and 88 back into normal position, this allows lever 88 to ride off of the incline over the screw 93 and engages its back end over the pin 82.

On the bracket arm 79 near its outer edge, I rigidly connect a peculiar shaped spring bracket 94, to which one end of a spring 95 is attached, the opposite end of said spring being attached to the stop lever 81.

A bearing 96 is attached to housing 1 on the pulley side, which supports the drive shaft. On the housing 1 near bearing 96, I rigidly connect a bracket 97 which carries a spring pawl 98, which operates in ratchet teeth 99 in clutch collar 14.

The spring pawl is rigidly connected at 100 on bracket 97, (see Fig. 1). On the pulley side of housing 1, near its forward end, I rigidly connect a stop pin 101, which extends out towards the pulley and limits the motion of lever 87. The spring pawl 98 is used for the following purpose; when the clutch mechanism is stopped, the spring pawl 98 drops into one of the three recesses 99 and thus keeps the collar 14 from rebounding and thus allows binding rolls (of usual construction in this class of clutches) in the clutch 96 from binding on the outer collar or wall 12, thus allowing the fly wheel to be free.

The shoe upper is marked 102, the button hole fly is marked 103, button fly 104, the button holes 105 and the buttons 106.

40 The shoe upper, button hole fly, button fly, button holes and buttons are shown to advantage in Figs. 15, 16, 17, 18 and 19, particularly in Fig. 17.

It will be noted that one pusher finger is higher than the other; and this is done to better enable said pusher fingers to push the button hole fly over the buttons on the button fly when the buttons are grasped and held by the button finger mechanism, so that 45 there will be no strain upon the button holes, as by this operation the button fingers push up on one side of the button hole first and when this side has been partly raised, the other pusher finger pushes up on its side, 50 thus no undue strain will result.

Each of the button grasping and holding fingers is provided with an oval slot 107 at the top or head; the sides of the button entering into these slots as the fingers are 60 brought together to grasp the button, thus buttons of varying diameter can be grasped and held by the button holding fingers.

When it is desired to operate the machine, the button hole fly 103, is placed onto the 65 closed button clasping fingers 50, as shown

in Fig. 15, that is, the operator places the five button holes 105, over the said button clasping fingers; the operator then exerts pressure on a foot treadle which releases the clutch and allows the drive shaft 8 to make 70 one revolution, which in turn moves cam shaft 3, one fourth of a revolution and by reason of cam 4 being attached to cam shaft 3 which also revolves one fourth of a revolution, thus allowing cam lever 23, and roller 75 24 to ride off of the nose 16 of cam 4, which turns shaft 20 in a downward direction and, by reason of levers 21 and 22 and links 49 and bearings 46 on studs 45 pulls down the cross bars 47 to which are attached the 80 shafts 57, with cone shaped heads 58, causes same (shafts 57 and cone shaped heads 58) to be pulled downward, which in turn allows arms 51 attached to button clasping fingers 50 to close; thus opening the two button 85 clasping jaws 50 to receive the buttons; at this point the machine automatically stops and frees the clutch allowing the pulley wheel 10 to revolve freely, the movements of this 90 operation result in the positioning of the parts as shown in Fig. 16. The fingers are now open as shown in Fig. 16 ready to receive the buttons and now the operator takes the button fly 104 and pulls it up and over, and then enters the buttons into the 95 open finger 50, as shown in Fig. 17; he then causes a pressure on the foot treadle of the machine which again operates the clutch, causing the drive shaft 8 to revolve three 100 complete revolutions and then automatically stopping same, these revolutions in turn drive the cam shaft 3 and cams 4, 5 and 6 which are rigidly attached thereto to revolve three quarters of a revolution; during the first quarter turn of the cam shaft of the 105 three quarter movement of the shaft 3, the cams 4 and 5 revolve into a position to allow the cam levers 23 and 26 and rollers 24 and 27 to ride up on the noses 17 and 18, thus causing rock shaft 20 to rock or move upward and move levers 21 and 22 with links 49 bearings 46 on its studs 45 to move upward also, thus pushing the shafts 57 with cone heads 58 up between the lower end of arms 51, thus spreading these arms 51 below 110 and causing the button fingers to close around the button; at the same time cam 5 which is revolved allows cam lever 26 and cam roller 27 to ride up on nose 18, thus moving cam lever 26 upward, and this lever 115 being fulcrumed on rock shaft 20 causes roller 36 and roller stud 35 (rigidly connected to bar 33), having at its outer ends the shafts 32 passing through bearings 31 which have at their top, a bar 34 rigidly attached thereto, to which bar there are attached, two downwardly extending bars 39, and to these bars 39 there are attached two 120 cross bars 40, these cross bars 40 are bearing bars for the slides 44 which carry the 125 130

pusher fingers 42 and 43; by reason of the cam roller 27 riding up on nose 18 of cam 5, the above and before described parts are all pushed up placing the pusher fingers 42 and 43 against the button hole fly 103, thus beginning to push the button hole fly over the button fingers 50 which are now clasped around the button, which is shown in Fig. 18. Upon the next quarter turn of the 10 above stated three quarter turn of shaft 3 the following operation results, to wit: the pusher fingers continue to push the button hole fly 103 over the closed button fingers 50 as they are holding the buttons, this upward 15 movement continues until the top of the pusher fingers is above the top of the button clasping fingers 50; and now during the last quarter turn of the three quarter turn of cam shaft 3, the cam roller 24 is 20 caused to ride off of the nose 17 on cam 4 thus releasing the shafts 57 with cone shaped heads 58, allowing the button fingers 50 to be opened, thus releasing the button; and now cam roller 27 rides up on nose 25 19 of cam 5 thus continuing to push fingers 42 and 43 in slide blocks 44 upward and pushing the button fly and the buttons out of and away from fingers 50; the fingers are still open and they must be closed for the 30 beginning of the next operation and this is done by reason of cam roller 24 riding up on nose 16 of cam 4, again pushing the shafts 57 with cone point heads 58 up into and between arms 51 causing the finger jaws 50 to close; the next operation is to bring the 35 pusher fingers 42 and 43 and slide blocks 44 back to normal positions and this is done by cam roller 27 riding off of nose 19 of cam 5 thus allowing the cam roller 32 on stud 35 40 to drop which pulls down the pusher fingers 42 and 43 and slide blocks 44 to normal position; this completes the last quarter turn of the three quarter turn of shaft 3; and at this point the clutch is automatically 45 stopped and the pulley wheel is free to revolve.

It will be understood that this machine may be so arranged that it can be operated by hand instead of by power, and that it 50 may be used for buttoning any other form or kind of material which must be buttoned the same as the flies of shoes, which may be used for some other purpose.

From the above description, it will be 55 seen that my new shoe buttoning machine, constructed according to my invention, is of an inexpensive and simple nature considering the work done, and it is especially well adapted for the purpose for which it is designed, 60 and it will also be obvious from the above description, that the same is capable of considerable modification without material departure from the principle and spirit of the invention, and for this reason I wish to be 65 understood as not limiting myself to the

precise form and arrangement of the several parts of the mechanism as herein set forth, in carrying out my invention in practice, and I wish to be understood that such modifications will still fall within the scope 70 of my invention.

What I claim as new and my invention and desire to secure by Letters Patent is:

1. In a shoe buttoning machine, initial means for grasping and holding the buttons 75 on the button fly and means for pushing the button hole fly over the buttons to connect with them, said means also releasing the buttons and the buttoned flies from the machine. 80

2. In a shoe buttoning machine, stationary initial means for grasping and holding the buttons on a button fly and means for forcing the button hole fly toward the button fly, so that the button holes will pass 85 over the buttons, the means for forcing the button hole fly over the buttons, initially pushing and operating on one side of the button hole and then upon the other side thereof. 90

3. In a shoe buttoning machine, means for grasping and holding buttons on a button fly, and upwardly and downwardly moving means for forcing the button hole fly over the buttons of the button fly, said last 95 named means also forcing the buttoned flies out of the machine. 95

4. In a shoe buttoning machine, stationary initial means for grasping and holding the head of a button on a button fly, and means for forcing the button hole fly over the buttons of the button fly, the means for grasping and holding the heads of the buttons capable of adjustment. 100

5. In a shoe buttoning machine, means 105 for grasping and holding the buttons on a button fly, and means for forcing the button hole fly over the buttons of the button fly, the latter means consisting of two separate relatively unmovable work engaging 110 parts, one higher than the other.

6. In a shoe buttoning machine, stationary initial means for receiving and grasping and holding the buttons on a button fly, and means for forcing the button hole fly over the buttons of the button fly, said means for grasping and holding the buttons on the button fly capable of adjustment so that buttons having varying spaces between them may be buttoned. 115 120

7. In a shoe buttoning machine, stationary initial means for grasping and holding the buttons on a button fly, and means for forcing the button hole fly over the buttons of the button fly, said means all capable of 125 adjustment, enabling the machine to operate on buttons varying in space from center to center.

8. In a shoe buttoning machine, initial stationary means for receiving and grasping 130

ing and holding the buttons on a button fly, and means for forcing the button hole fly over the buttons of the button fly and expelling the buttoned flies out of the machine.

9. In a shoe buttoning machine, initial stationary means for receiving and grasping and holding the head of each of the buttons on a button fly, and an upwardly and 10 downwardly moving means for forcing the button hole fly over the buttons of the button fly.

10. In a shoe buttoning machine, stationary initial means for receiving and grasping and holding the head of each of the buttons on a button fly, and means for forcing the button hole fly over the buttons of the button fly, the latter means operating outside the former means.

20 11. In a shoe buttoning machine, stationary means for holding and supporting a button hole fly through the button holes thereof, said means also grasping and supporting the buttons on a button fly and 25 means for buttoning said flies.

12. In a shoe buttoning machine, stationary means for holding and supporting a

button hole fly through the button holes thereof, said means also grasping and supporting the buttons on a button fly simultaneously and means for buttoning said flies.

30 13. In a shoe buttoning machine, stationary fingers for supporting and holding a button hole fly and also capable of receiving, grasping and holding the buttons on a button fly and means for buttoning said flies together.

35 14. In a shoe buttoning machine, stationary means over which button holes on the button fly are manually placed to support the work, said means also capable of receiving, grasping and holding buttons on the button fly to support the same in the machine, and means for buttoning said flies 40 together and for expelling the buttoned flies out of the machine.

45 In testimony whereof I affix my signature in the presence of two witnesses.

LOUIS J. VAN GELPEN.
